SUPPORTING CASING FOR COLLAPSIBLE
TUBE, HAVING EXTRUDING MECHANISM
FOR THE CONTENTS OF SAID TUBE

Alfred B. Smith, Houston, Tex.

Application November 12, 1946, Serial No. 709,155

3 Claims. (Cl. 222—99)

1

This invention relates to a supporting casing for collapsible tube, having extruding mechanism for the contents of said tube and has particular relation to an apparatus for dispensing the plastic contents of tubes such as tooth paste, shaving cream and the like.

Another object of the present invention is to provide a dispenser of the character described embodying a frame adapted to be anchored to a wall or other fixed support with a rotatable spindle, or key, mounted in the frame and shaped to receive the closed end of the tube, and, by rotation, to force the contents out of the neck of the tube, in combination with an enclosing housing which may be readily applied to or removed from the frame.

A further object of the present invention is to provide, in a dispenser of the character described, severing means for completely removing the ejected material and for closing the neck of the tube.

With the above and other objects in view the invention has particular relation to certain novel features of construction, operation and arrangement of parts, an example of which is given in this specification and illustrated in the accompanying drawings, wherein:

Figure 1 is a side elevation of the dispenser, partly broken away.

Figure 2 is a sectional view taken on the line 2—2 of Figure 1.

Figure 3 is a bottom end view; and

Figure 4 is a cross-sectional view taken on the line 4—4 of Figure 1.

Referring now more particularly to the drawings wherein like numerals of reference designate the same parts in each of the figures, the numeral 1 designates a bracket adapted to be secured to a fixed support such as a wall 2.

Fixed to and extending outwardly from the bracket there is a shank 3 and secured to the outer end of this shank there is an annular band 4, said bracket, shank and band constituting a frame.

The band 4 is provided with opposing bearings 5, 5 and rotatably mounted in these bearings there is a cylindrical shaped key 6 which is provided with a lengthwise slot 7 to receive the closed end of a tube 8 containing the material to be dispensed and which is formed of flexible material.

The other end of the tube 8 is formed with a tubular neck 9 which is externally threaded and a disc-like cap 10 may be screwed onto said neck, as best illustrated in Figure 2.

2

Eccentrically pivoted on the lower side of the cap 10 there is a disc-like closure plate 11 which also serves as a cutter and whose free side is provided with a pressure plate 12 whereby said disc may be swung to open or closed position.

One end of the key 6 is extended and fixed on said extended end there is a wing grip 13 by means of which the key may be turned.

There is an inverted cup-shaped housing 14 whose upper end is permanently closed and whose lower end is open.

The upper side of the cap 10 is reduced in diameter forming an external, annular, upwardly facing shoulder 15 and the lower end of the housing 14 may be fitted over said reduced portion of the cap closely and fitted against said shoulder.

This housing has two longitudinal slots 16 and 17 extending from the open end thereof the required distance toward the closed end thereof, the former to receive the extended end of the key 6 and the latter to receive the shank 3 when the housing is fitted onto the frame, and it will be noted from an inspection of Figure 2 that the extended end of the key 6 is formed with an annular groove 18 which receives the side margins of the slot 16.

In use, with the frame secured to a support the closed end of the tube 8 may be fitted through the slot 7 and the cap 10 may then be screwed onto the neck 9 with the disc 11 in closed position. The housing 14 may then be fitted over the frame, as shown in Figures 1 and 2, with its free end fitted onto the cap 10. The disc-like closure 11 may then be opened and the key 6 then turned until the desired quantity of the contents of the tube have been forced out whereupon the closure 11 may be swung to closed position.

As the tube 8 is emptied the housing 14 will move upwardly and when the tube is emptied and the housing has reached the limit of its upward movement the housing may be removed and the empty tube 8 detached and a full tube substitute for it in an obvious manner.

The drawings and description are illustrative merely while the broad principle of the invention will be defined by the appended claims.

What I claim is:

1. A dispenser comprising, a frame adapted to be secured to a stationary support and including a shank and an annular band secured to the shank, bearings in the band, a transverse key mounted to rotate in the bearings and having an extended end, said key having a transverse slot to receive the closed end of a flexible tube which

is adapted to roll about the key upon rotation of the key, a cap having a central opening to receive the neck of the tube, a housing adapted to be fitted snugly over the band of the frame and moveably carried by said frame, said housing having longitudinal slots leading from the open end thereof to receive the shank and the extended end of the key, respectively, said cap having a reduced upper end which fits snugly into the lower end of the housing.

2. A dispenser comprising, a frame adapted to be secured to a stationary support and including a shank and an annular band secured to the shank, bearings in the band, a transverse key mounted to rotate in the bearings and having an extended end, said key having a transverse slot to receive the closed end of a flexible tube which is adapted to roll about the key upon rotation of the key, a cap having a central opening to receive the neck of the tube, a housing adapted to be fitted snugly over the band of the frame and moveably carried by said frame, said housing having longitudinal slots leading from the open end thereof to receive the shank and the extended end of the key, respectively, and means on said extended end for rotating the key, said cap having a reduced upper end which fits snugly into the lower end of the housing.

3. A dispenser comprising, a frame adapted to be secured to a stationary support and including a shank and an annular band secured to the shank, bearings in the band, a transverse key mounted to rotate in the bearings and having an

extended end, said key having an extended end and a transverse slot to receive the closed end of a flexible tube which is adapted to roll about the key upon rotation of the key, a cap having a central opening to receive the neck of the tube, a housing moveably fitted over the band and supported on the cap, said housing having two longitudinal slots leading from the open end thereof to a point spaced from the closed end thereof, one of said slots accommodating said shank and the other of said slots accommodating said extended end of the key, and means on said extended end for rotating the key.

ALFRED B. SMITH.
